RELAXATION INDUCING APPARATUS

Wilhelm W. Brockway and Leslie Le Cron, Los Angeles, and Jack H. Young, Playa Del Ray, Calif.

Application January 4, 1947, Serial No. 720,268

15 Claims. (Cl. 171—97)

1

This invention relates to apparatus for inducing relaxation and sleep. In general, the invention has as its object to provide an improved apparatus for producing a series of interrupted sound impulses or light flashes (or both) repeated in regular succession at uniformly spaced intervals of time of proper duration for maximum relaxing effect. The sound impulses are of a type which we prefer to designate as "tones," being preferably of a musical character rather than mere noise, and also preferably of a monotone character (single pitch) although succeeding notes of different pitch, recurring in a regular pattern or melody, may be employed.

A specific object of our invention is to provide a sleep-inducing apparatus that can be turned on at the bedside of the patient, be allowed to continue operating while the patient goes to sleep, and then be relied upon to automatically cease operation after a predetermined interval of time has passed.

One of the main problems with which the present invention deals is that of providing an extremely simple and inexpensive timing mechanism for controlling the tones and light flashes. Specifically, in this connection, the invention aims to provide an arrangement in which the motor device utilizes the movable arm of the light control switch in connection with a bi-metal bow, intermittently heated by the current passing through the switch, to provide a reciprocating motor for actuating a tone-producing device and, at the same time, driving a short train of gears in which is incorporated an adjustable timing device for determining the period of operation.

Other objects of the invention will become apparent in the ensuing specifications and claims, in connection with the appended drawings, in which:

Fig. 1 is a front view of a sleep-inducing device embodying our invention;

Fig. 2 is a vertical longitudinal sectional view of the apparatus with the front removed;

Fig. 3 is a vertical transverse sectional view of the time-setting mechanism, taken on the line 3—3 of Fig. 2; and

Fig. 4 is a detail sectional view of the time-setting mechanism, taken on the line 4—4 of Fig. 2.

As an example of one form in which the invention may be embodied, we have shown in the drawings a sleep-inducing apparatus which is mounted in a rectangular case 5 which may include an integral front wall 6 and a removable rear wall 7 secured, as per example, by screws 8.

2

The apparatus may, as shown, be largely supported upon the rear wall 7.

Light is produced by a small electric lamp 9 mounted in a lamp socket 10 which is carried on a bracket 11. The lamp 9 is mounted directly behind an opening in the front wall 6 of the casing 5, in which opening is secured a lens or bubble 12 of translucent glass or plastic material, preferably colored.

The tones are produced by a musical reed 13 when plucked by a plectrum 14. The plectrum 14 is pivoted at 15 upon the movable end of a flexible switch arm 16. The switch arm 16 carries a contact 17, which cooperates with a contact 18 carried by a flexible switch arm 19, to provide a switch that is adapted to intermittently close and open to make and break a circuit for energizing the lamp 9.

For closing and opening the switch, the movable switch arm 16 is flexed back and forth by a thermo-responsive, bi-metal bow 20, the ends of which are secured to the switch arm 16 and the intermediate portion of which is wound with a heating coil 21. One end of the coil 21 is connected to the contact 17 and thus to the switch arm 16, which is of metal, and the other end of the coil 20 is connected to a bus bar 22.

The bracket 11, switch arms 19 and 16, bus bar 22 and reed 13 are mounted between successive blocks of insulating material 23, 24, 25, 26, and 27, secured to and supported in stacked relation upon a horizontal arm 28 of a bracket 29 secured at 30 to the rear wall 7 of the casing 5. These parts are secured together by bolts 31 extending through the entire stack and clamping the parts tightly together. The bolts 31 do not, however, make contact with the bracket 11, switch arm 16, 19, or bus bar 22, all of which form parts of the electrical circuit of the apparatus. These parts may be provided with openings sufficiently larger than the diameter of the bolts 31 to permit the bolts to pass therethrough without contact.

Connected to a household wiring system by a service cord 32, the apparatus may be turned off and on by an electric switch 33 which is shown as being mounted on the bottom of the casing 5, with the cord 32 coming up through the bottom 5. From the switch 33, a lead wire 34 extends to the bus bar 22, and another lead wire 35 extends to the upper switch arm 19. The bus bar 22 is connected to the bracket 11 by a conductor 36, and the rear contact of the socket 10 is connected to the switch arm 16 by a conductor 37. The side contact of the socket 10 is connected electrically to the bracket 11, while the rear contact is insu-

lated therefrom, as indicated at 38. Thus, there are established the following circuits:

To the lamp 9—conductor 34, conductor 36, bracket 11, socket 10, conductor 37, switch arm 16, contacts 17 and 18, switch arm 19, conductor 35;

To heating coil 21—conductor 34, bus bar 22, coil 21, contacts 17 and 18, upper switch arm 19, conductor 35.

The plectrum 14 has at its lower end a hook 39 that barely engages the end of the reed 13 as the switch arm 16 is moved upwardly. At the other end of the plectrum 14 is a pawl 40 which engages, consecutively, the teeth of a ratchet wheel 41. Each closing movement of the switch arm 16 will advance the ratchet wheel 41 a distance corresponding to the length of one tooth. The parts are so arranged that, as the pawl 40 thus moves upwardly, the plectrum 14 will, after bending the reed 13 upwardly, disengage from the end of the reed so as to permit the reed to vibrate and to produce a musical note. Such disengagement may be facilitated by a slight counterclockwise rotation (as viewed in Fig. 2) of the plectrum and pawl lever about the pivot 15, caused by the path of movement enforced by the periphery of the ratchet wheel 41. Alternatively, the disengagement may be caused by the foreshortening of the reed 13 as it is bent upwardly into arcuate shape.

Any suitable spring means acting between the arm 16 and the pawl plectrum lever, such as the light leaf spring 42, may be employed for constantly urging the pawl 40 into engagement with the ratchet wheel 41.

The ratchet wheel 41 is journaled in the casing 5 on a shaft 43 and drives a pinion 44 which meshes with a gear 45. The gear 45 is journaled in the casing 5 on a shaft 46 and drives a pinion 47 which meshes with a gear 48. The gear 48 is journaled in the casing 5 on a shaft 49 and has clutching coaction with a disc 50 which is also journaled on the shaft 49, being provided with a tubular hub 51 into which the shaft 49 extends. The hub 51 extends through an opening in the front wall 6 of the casing and to the outer end of the hub is secured a knob 52 having a pointer 53. The pointer cooperates with a dial 54 on the outer face of the wall 6, the dial 54 being calibrated to indicate minutes.

The clutching connection between the gear 48 and disc 50 may comprise simply a plurality of teeth 54 formed by punching tongues out of the web of the gear 48 and a single tooth 55 in the form of a tongue punches out of the disc 50. The hub of the gear 48 is loosely mounted on the shaft 49 to permit the gear to shift axially, and a coil spring 56 may be employed to urge the gear into clutching engagement with the disc 50. The coil spring 56 may encircle the hub of the gear and be under compression between the gear and a boss 57, in which the shaft 49 is mounted.

In the periphery of the disc 50 is a notch 58 which, when the pointer 53 is opposite the zero mark on the dial 54, is adapted to receive a lug 59 on the end of the switch arm 19. The switch arm 19, which is of resilient metal, is biased toward a position in which the lug 59 rests in the bottom of the notch 58, and will assume this position when the notch 58 is brought into registry with the lug 59. In this position, the contact 18 is withdrawn out of reach of the contact 17 so that it is impossible for the switch to close. Thus, the dropping of the lug 59 into the notch 58

serves to shut off the apparatus, and the switch 33 may, if desired, be dispensed with.

In the operation of our improved sleep-inducing apparatus, the switch 33 is closed in order to establish an electric circuit up to the bus bar 22 and upper switch arm 19. The knob 52 is then rotated to bring the pointer 53 opposite a position on the dial 54 corresponding to the number of minutes that it is desired to have the apparatus operate. When the apparatus is cold, the arm 16 will be relatively straight, so as to position the contact 17 where the contact 18 will engage the same as the result of the rotation of the knob 52. That is, the lug 59 will be forced out of the notch 58 by a camming surface on one side of the notch 58 as the knob 52 is rotated away from the zero position, thus moving the contact 18 into engagement with contact 17.

With the switch thus closed, a circuit for energizing lamp 9 will be established from switch 33 to conductor 34, conductor 36, bracket 11, socket 10, conductor 37, lower switch arm 16, contacts 17 and 18, upper switch arm 19, and conductor 35. Simultaneously, a circuit will be established to heating coil 21 through conductor 35, bus bar 22, switch contacts 17 and 18, upper switch arm 19, and conductor 35. Each of these circuits will remain established until the heating of the bimetal bow 20 by the heating coil 21 has caused the bow to expand to the point where it overcomes the inherent resiliency of the arm 16 and causes the latter to bow downwardly to the position shown in Fig. 2. This downward movement will occur with a snap action owing to the fact that in the raised position of the contact 17, the arm 16 is bowed reversely to its bowing in the lower position shown in Fig. 2. The movement to the lower position brings the hook 39 beneath the end of the reed 13, the lower surface of the hook 39 being cammed so as to permit it to slip by the end of the reed, rotating the plectrum 14 slightly counter-clockwise against the resistance of the spring 42 as it thus passes the reed. The parts are thus brought to the positions shown in Fig. 2.

With the switch thus opened, the heating coil 21 commences to cool. The cooling of the coil and bow 20 causes the latter to undergo a contracting stress which, when the cooling has progressed to a certain point, will overcome the bow in the arm 16 and cause it to snap back to its reversely bowed position, bringing the contact 17 into engagement with the contact 18. At the same time, the plectrum 14 will pluck the reed 13 to produce a musical note coincident with the re-lighting of the lamp 9. This completes one cycle of operation, which will be followed by subsequent similar cycles of operation as long as the lug 59 remains in engagement with the periphery of the disc 50. When the time period predetermined by the setting of the knob 52 has elapsed, the lug 59 will drop into the notch 58, removing the contact 18 from the reach of the contact 17, as previously stated and discontinuing the operation of the apparatus.

We claim:

1. In a device for inducing relaxation, a switch embodying a movable switch element, a device for producing sensory impulses in response to movement of said switch element, a thermo-responsive device including a heating coil controlled by said switch, for alternately moving said switch element to switch closing and switch opening positions, and timing mechanism actuated by the movements of said switch element, for rendering

the device inoperative at the end of a predetermined time interval.

2. In a device for inducing relaxation, a switch embodying a pair of movable switch elements one of which is adapted to actuate, a device for producing sensory impulses, a thermo-responsive device including a heating element controlled by said switch, for intermittently moving said one switch element between said positions, and timing mechanism actuated by the movements of said one switch element, for holding the other switch element in a position in which it may be intermittently contacted by said one switch element for a predetermined period of time and then causing the movement of said other switch element to a position removed from the reach of said one switch element, thereby terminating the operation of the device.

3. In a device for inducing relaxation, a switch including a pair of movable switch elements one of which is adapted to actuate, a device for producing sensory impulses, thermo-responsive means including a heating coil controlled by said switch, for intermittently moving said one switch element between switch closing and switch opening positions, means actuated by the movements of said one switch element, said means including a member that is movable into engagement with said other switch element and adapted to maintain said other switch element in a position in which it may be engaged by said one switch element from a starting point to a point where said member is cut away to release said other switch element to a position withdrawn out of reach of said one switch element, thereby terminating the operation of the device, and means for adjusting the starting position of said member whereby to vary the distance between said starting point and said release point, thereby to vary the period of operation of the device.

4. In a relaxation-inducing device, a switch embodying a pair of movable switch elements, means controlled by said switch for moving one of said elements between switch opening and switch closing positions, one of said switch elements being adapted, in its movements between said positions, to actuate an element for producing sensory impulses, timing mechanism including a member having a bearing portion for engaging the other switch element and thereby holding it in a position in which it may be contacted by said one switch element, from a starting position to a release position in which said member is adapted to release said other switch element for movement to a position withdrawn out of reach of said one switch element, thereby terminating the operation of the device, and means for setting the starting position of said member in order to vary the distance between the starting position and the release position and thereby vary the period of operation of the device.

5. In a device for inducing relaxation, including a means for producing sensory impulses, the combination of: a switch embodying a pair of movable switch elements, means for intermittently moving one of said switch elements between switch closing and switch opening positions, the other switch element being biased toward an inoperative position removed from the reach of said one switch element, timing mechanism including a member having a bearing portion for engaging said other switch element and maintaining it in a position in which it may be contacted by said one switch element in the switch closing position thereof, said member being mov-

able from a starting position to a release position in which it is adapted to release said other switch element for movement to the inoperative position, thereby terminating the operation of the device, and having means for setting the starting position so as to vary the period of operation of said device said one switch element being adapted to actuate said sensory impulse producing means.

6. In a device for inducing relaxation, including 10 a tone producing device, the combination of: a switch embodying a movable switch element, means carried by said movable switch element and operable to intermittently actuate said tone-producing device in timed relation to the movements of said switch element, and a thermo-responsive device including a heating element controlled by said switch, for intermittently moving said movable switch element between switch closing and switch opening positions.

7. In a relaxation-inducing device including 20 a tone-producing reed and an electric lamp for producing sleep-inducing light flashes, the combination of: a switch including a movable switch element, means controlled by said switch for intermittently moving said switch element between switch closing and switch opening positions in which said lamp is illuminated and extinguished respectively, and a plectrum carried by said movable switch element and arranged to pluck said reed during movement of said switch element toward one of said positions.

8. In a device for inducing relaxation including 30 tone-producing means and an electric lamp for producing sleep-inducing light impulses, the combination of: an electric switch including a switch element movable between a switch closing position in which said lamp is energized and a switch opening position in which said lamp is extinguished, and means for intermittently moving 40 said movable switch arm between said positions, said switch being arranged to actuate said tone-producing means intermittently in timed relation to its own movement.

9. In a relaxation-inducing device including 45 tone-producing means and an electric lamp for producing sleep-inducing light impulses, the combination of: an electric switch embodying a switch element movable between a switch closing position in which said lamp is energized and a switch opening position in which said lamp is extinguished, means for intermittently moving said switch element between said positions, said last means including means intermittently energized and de-energized by the closing and opening of 50 said switch, said switch being arranged to actuate said tone-producing means intermittently in timed relation to its own movements, and timing mechanism, actuated by said movable switch element, adapted to render said switch inoperative 55 at the end of a predetermined period of operation.

10. In a relaxation-inducing device including 60 a tone-producing reed, a combination including: an electric lamp for producing a relaxation-inducing light impulse, an electric switch including 65 a pair of movable switch elements, one of which is reciprocal between a switch closing position in which said lamp is energized and a switch opening position in which said lamp is extinguished, means for intermittently moving said one switch element between said positions, said last means including actuating means energized and deenergized by the closing and opening of said switch respectively, a plectrum carried by said movable 70 switch element and adapted to pluck said reed 75

during movement of said movable switch element toward one of said positions, and timing mechanism including a rotatable member having a bearing portion for engaging said other switch element and maintaining it in a position in which it may be contacted by said one switch element, until said rotatable member reaches a position in which it is adapted to release said other switch element for movement to an inoperative position, out of reach of said one switch element, and driving means actuated by said one switch element in its movements between said positions, for slowly rotating said rotatable member from a starting position to said release position.

11. Sleep-inducing apparatus as defined in claim 10, in which said driving mechanism includes a pawl pivoted to said one switch element, a ratchet wheel actuated by said pawl, and a train of gearing connecting said ratchet wheel to said rotatable member.

12. In a sleep-inducing apparatus including a tone-producing reed, the combination of: a switch including a pair of movable switch elements, one of which is movable between switch closing and switch opening positions, thermo-responsive means for intermittently moving said one switch element between said positions, said thermo-responsive means including a heating coil energized and de-energized by the closing and opening of said switch respectively, a lever pivoted to said movable switch element, one end of said lever being provided with a plectrum for plucking said reed as said one switch element moves toward the switch closing position, and timing mechanism including a ratchet wheel and a pawl on the other end of said lever for intermittently advancing said ratchet wheel, a train of gearing driven by said ratchet wheel, and a notched disc driven by said train of gearing and adapted to engage the other of said switch elements to hold it in a position for engagement by said one switch element until it has been rotated to a release position in which it permits said other switch element to move to an inoperative position out of reach of said one switch element, thereby terminating the operation of said device.

13. Sleep-inducing apparatus as defined in claim 12, including an electric lamp for producing sleep-inducing light impulses energized by the closing of said switch and de-energized by the opening of said switch.

14. In a sleep-inducing apparatus comprising means for producing sensory impulses, the com-

bination of: an electric switch for intermittently actuating said means, said switch including a pair of movable elements, one of which is biased away from an operative position in which it may be engaged by the other switch element toward an inoperative position out of reach of said other element, means for intermittently moving said other switch element between a switch closing position in which it is adapted to engage said one switch element when the latter is in its operative position, and a switch opening position, means for reciprocating said other switch element between said positions, said means including electrical actuating means energized and de-energized respectively by the closing and opening of said switch, and timing mechanism including a ratchet wheel, a pawl carried by said other switch element and operable to advance said ratchet wheel as said other switch element moves toward one of said positions, a train of gears driven by said ratchet wheel, a rotatable disc the periphery of which is adapted to bear against said one switch element to maintain the latter in its operative position until the disc has been rotated to a release position in which it is provided with a notch permitting said one switch element to move to the inoperative position, a clutch for transmitting drive from said train of gears to said disc, and means for setting said disc in various positions of said notch with reference to said one switch element to vary the period of operation of the device, said clutch being adapted to release the driving connection between said train of gears and said disc to permit said setting.

15. Sleep-inducing apparatus as defined in claim 14, in which said clutch is a one-way clutch and in which the setting is effected by rotating said disc ahead of the train of gears in the direction in which it is driven by said clutch.
